UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed February 27, 1932. Serial No. 595,453.

This invention relates to car roofs of the type wherein the metal roof sheets are shaped, arranged and rigidly secured together to form a roof consisting of alternating ribs and channels, and the roof as a whole functions mechanically as a beam supported on the side plates of the car.

The principal object of the present invention is to provide a roof of the above type with members which serve to increase the compression strength of the roof and which also constitute means for securing an insulating lining to the underside of the roof. Other objects are simplicity and cheapness of construction, ease of assembly and fewness of parts. The invention consists in increasing the compressive strength of the hollow roof ribs by means of wooden members that are located in said ribs and serve as nailing strips for an insulating lining. It also consists in the parts and in the combinations and arrangements of parts hereinafter described and claimed.

Fig. 1 is a plan view of a portion of an insulating car roof embodying my invention;

Fig. 2 is a vertical transverse section on the line 2—2 in Fig. 1;

Fig. 3 is a vertical longitudinal section through the roof on the line 3—3 of Fig. 1;

Figs. 4 and 5 are views similar to Fig. 3, showing modified constructions.

In the present roof construction, the metal roof sheets 1 extend from side plate 2 to side plate 2 of the car with their ends turned down, as at 3, and riveted or otherwise rigidly secured to such side plates by rivets 4. Conformably to the so-called neutral axis type of roof, the roof sheets are shaped, arranged and rigidly secured together to form a roof consisting of alternating flat-topped ribs A and flat-bottomed channels B that extend from side plate to side plate of the car, whereby the roof as a whole functions mechanically as a beam supported on said side plates. The hollow ribs A and the channels B are preferably of substantially equal cross-sectional area, whereby the neutral axis of the roof is substantially midway between the tops of said ribs and the bottoms of said

channels, said ribs decreasing in height from a maximum of the ridge to points at or near the eaves where they merge into the plane of the bottoms of the channels.

As shown in the drawing, each roof sheet 1 is provided along each side edge with an upstanding seam flange 5 and has its longitudinal middle portion offset upwardly with respect to the side portions thereof, thus forming one of the hollow roof ribs A, such middle portion and the side portions being integrally connected throughout their length by web members 6 that form the two sides of said rib and one side of the channels B on opposite sides thereof. The roof sheets 1 are arranged side by side crosswise of the car with their depending eaves flanges 3 riveted to side plates 2 and with seam caps 7 straddling the upstanding seam flanges 5 of adjacent roof sheets and rigidly secured thereto by rows of rivets 8 located preferably along the neutral axis of the roof. The seam caps 7 are provided with outstanding base flanges 9 that rest on the body portions of adjacent roof sheets. By this arrangement, the raised middle portions of the roof sheets form the tops of the hollow roof ribs A, the side portions of adjacent roof sheets form the bottoms of the roof channels B, and the web members 6 that connect said middle portions with said side portions form the sides of both the ribs and channels; adjacent seam flanges 5 and the seam caps 7 therefor cooperate to form rigid upstanding seams that are located along the middle of the channels.

Located within each hollow roof rib A is a reinforcing member 10, preferably in the form of a wooden strip, that extends from side plate to side plate midway between the sides of said rib, such reinforcing member being located wholly within said rib with its bottom surface flush with the undersides of the roof channels B on opposite sides of said rib. The wooden reinforcing member 10 is secured to the hollow roof rib A by means of brackets located preferably adjacent to and intermediate between the ridge and eaves of the car. As shown in Fig. 3, each bracket for securing the wooden reinforcing member 10 to the hollow roof rib A comprise two an-

gle-shaped members 11 arranged with one flange up and riveted flatwise to the underside of the top portion of said rib and with the other flange down. The depending flanges of the two angles 11 are spaced far enough apart to receive the wooden reinforcing member 11 therebetween; and the wooden reinforcing member is removably secured between said flanges by means of a horizontal bolt 12.

10 In the modified construction shown in Fig. 4, the supporting bracket for the wooden reinforcing member is shown in the form of an inverted channel 11a, whose web portion is secured flatwise to the underside of the hollow roof rib A by means of rivets. This inverted channel-shaped bracket straddles the reinforcing member 11, which is secured to said bracket by a bolt 12a that extends horizontally through said reinforcing member and the depending side flanges of said bracket.

15 In the construction shown in Fig. 5, the supporting bracket for the rib reinforcing member 11 is shown in the form of a Z-shaped member 11b that has one of its flanges riveted or otherwise rigidly secured to the undersurface of the hollow roof rib. The other flange of the Z-shaped bracket 11b projects beneath the wooden reinforcing member 11; and a bolt 12b passes horizontally through said reinforcing member and the web portion of said bracket.

20 The wooden reinforcing strips 11 not only greatly strengthen and increase the roof against compression and buckling stresses, but they also serve as nailing strips to attach an insulating lining to the underside of the roof. As shown in the drawing, the insulating lining preferably comprises tongue-and-groove boards 13 that extend longitudinally of the roof preferably in contact with the undersides of the channels and are nailed or otherwise secured flatwise to the bottoms of the wooden reinforcing strips 11 for the hollow roof ribs A.

25 By the arrangement described, the wooden reinforcing members serve to reinforce and stiffen the middle portions of the hollow roof ribs against compression and buckling stresses, whereby the strength of the roof is greatly augmented when considered as a beam. These wooden reinforcing members also serve as nailing strips for the insulating lining, which can be used without greatly decreasing the headroom in the car; and the brackets permit the combined nailing and reinforcing strips to be quickly and easily attached to and removed from the hollow roof ribs.

30 What I claim is:

1. A car roof comprising hollow ribs alternating with channels, said ribs and channels being of substantially equal widths, whereby the neutral axis of the roof is substantially midway between the tops of said

35 ribs and the bottoms of said channels, wooden reinforcing members being located within said ribs substantially midway between the sides thereof, and means for removably securing said wooden strips to said ribs.

2. A car roof comprising hollow flat-topped ribs alternating with flat-bottomed channels, said ribs and channels being of substantially equal widths, wooden reinforcing members located within said ribs near the middle thereof, and means for removably securing said wooden strips to the undersides of said ribs.

3. A car roof comprising hollow ribs alternating with channels, said ribs and channels being of substantially equal widths whereby the neutral axis of the roof is substantially midway between the tops of said ribs and the bottoms of said channels, wooden reinforcing members located within said ribs substantially midway between the sides thereof, means for removably securing said wooden reinforcing members to said ribs, and an insulating lining located beneath said roof and secured to said reinforcing members.

4. A car roof comprising hollow ribs alternating with channels, said ribs and channels being of substantially equal widths whereby the neutral axis of the roof is substantially midway between the tops of said ribs and the bottoms of said channels, wooden reinforcing members located within said ribs substantially midway between the sides thereof, with their bottom surfaces substantially flush with the undersides of said channels, means for removably securing said wooden strips to said ribs, and an insulating lining located beneath said roof and secured to said reinforcing members.

5. A car roof comprising hollow ribs alternating with channels, said ribs and channels being of substantially equal widths, whereby the neutral axis of the roof is substantially midway between the tops of said ribs and the bottoms of said channels, wooden reinforcing members located within said ribs substantially midway between the sides thereof, and means for removably securing said wooden reinforcing members to said ribs, said means comprising bracket members rigidly secured to the undersides of said ribs and bolts for removably securing said wooden reinforcing members to said brackets.

6. A car roof comprising hollow ribs alternating with channels, said ribs and channels being of substantially equal widths, whereby the neutral axis of the roof is substantially midway between the tops of said ribs and the bottoms of said channels, wooden reinforcing members located within said ribs substantially midway between the sides thereof, means for removably securing said wooden reinforcing members to said ribs,

said means comprising bracket members rigidly secured to the undersides of said ribs and bolts for removably securing said wooden reinforcing members to said brackets, and an insulating lining located beneath said roof and secured to said wooden reinforcing members.

7. A car roof comprising hollow ribs alternating with channels, said ribs and channels being of substantially equal widths, whereby the neutral axis of the roof is substantially midway between the tops of said ribs and the bottoms of said channels, reinforcing members located within said ribs substantially midway between the sides thereof, and means for removably securing said reinforcing members flatwise to the undersides of said ribs with their undersides substantially flush with the undersides of said channels, said means comprising bracket members rigidly secured to the tops of said ribs and bolts for removably securing said reinforcing members to said brackets.

8. A car roof comprising hollow ribs alternating with channels, said ribs and channels being of substantially equal widths, whereby the neutral axis of the roof is substantially midway between the tops of said ribs and the bottoms of said channels, and wooden reinforcing members located within said ribs substantially midway between the sides thereof, and means for removably securing said wooden reinforcing members to said ribs, said means comprising brackets rigidly secured to the tops of said ribs and bolts for removably securing said reinforcing members to said brackets, said bracket members comprising angle-shaped members having one flange secured to a roof rib and the other flange located along side of one side of the reinforcing member thereon and provided with an opening for said bolt.

9. A car roof comprising hollow ribs alternating with channels, said ribs and channels being of substantially equal widths, whereby the neutral axis of the roof is substantially midway between tops of said ribs and the bottoms of said channels, wooden reinforcing members located within said ribs substantially midway between the sides thereof, inverted channel-shaped members located within said ribs with their webs permanently secured to the tops thereof and with their flanges straddling said wooden reinforcing members, and bolts passing through said flanges and said wooden reinforcing members.

10. A car roof comprising hollow ribs alternating with channels, said ribs and channels being of substantially equal widths whereby the neutral axis of the roof is substantially midway between the tops of said ribs and the bottoms of said channels, wooden reinforcing members located within said ribs substantially midway between the sides

thereof, Z-shaped bracket members located within said ribs with one flange secured to the undersides thereof and with the other flange extending beneath said reinforcing members, and bolts passing through said reinforcing members and the webs of said bracket members.

Signed at New Kensington, Pennsylvania, this 23rd day of February, 1932.
